UNITED STATES PATENT OFFICE

ROBERT E. PASLAY, OF ABERDEEN, WASHINGTON, ASSIGNOR TO HOKER-POKER COMPANY, OF ABERDEEN, WASHINGTON, A CORPORATION OF WASHINGTON

DESIGN FOR A GAME BOARD

Application filed September 30, 1929. Serial No. 32,899. Term of patent 14 years.

To all whom it may concern:

Be it known that I, ROBERT E. PASLAY, a citizen of the United States, residing at Aberdeen, in the county of Grays Harbor and State of Washington, have invented a new, original, and ornamental Design for Game Boards, of which the following is a specification, reference being had to the accompanying drawing, forming part thereof.

The figure is a plan view of a game board, showing my new design. Various color combinations may be used with respect to all parts of the board except the cards.

I claim:

The ornamental design for a game board, as shown.

ROBERT E. PASLAY.
